UNITED STATES PATENT OFFICE

131,193

DESIGN FOR A RADIO PANEL

Herman Dean, Borger, Tex.

Application September 3, 1941, Serial No. 103,146

Term of patent 3½ years

To all whom it may concern:

Be it known that I, Herman Dean, a citizen of the United States, residing at Borger, in the county of Hutchinson and State of Texas, have invented a new, original, and ornamental Design for a Radio Panel, of which the following is a specification, reference being had to the accompanying drawing, forming part thereof.

Figure 1 is a front elevational view of the radio panel, showing my new design.

Figure 2 is a plan view thereof.

The drawing is ruled for color.

I claim:

The ornamental design for a radio panel, as shown and described.

HERMAN DEAN.
